Elemir J. Ney, of Lowell, Mass.
Assignor to
Lowell Manufacturing Co.
Letters Patent No 1299, dated Aug. 7 1860.

The schedule referred to in these Letters Patent and making part of the same.

To all whom it may concern;

Be it known that I, Elemir J. Ney, of Lowell, in the County of Middlesex, and State of Massachusetts, have originated and designed a new pattern for Carpets, or other fabrics, of which the following is a full, clear and exact description, reference being had to the accompanying drawings, making part of this specification.

1. 2. 3 & 4, in the corners when matched from a four pointed figure resting on a spotted ground with an irregular border, centre A, consists of a group of leaves and flowers resting on a plain ground, Surrounding centre A, is the band B, which is itself surrounded by a belt of small balls 5. C & D, at the sides and E, & F, at the ends of the design when matched from two eight pointed figures in the centres of which are small stars.

The remaining portions of the design are occupied by the branchwork 6.

The colors employed for the different portions of the design may be varied to suit the taste and wish of the manufacturer.

Claim.

What I claim as my invention and desire to secure by Letters Patent, is the design or pattern for Carpets, and other fabrics, herein set forth.

Witnesses.
